COLLAPSIBLE TUBE

Burl E. Harman, Henryetta, Okla.

Application June 4, 1942, Serial No. 445,781

5 Claims. (Cl. 222—386)

This invention relates to a collapsible tube and provides a construction adapted for use as a substitute for metallic collapsible tubes such as are used to contain toothpaste, shaving cream, ointments and various other goods.

It is particularly aimed to provide a construction which will be convenient and sanitary and economical to manufacture.

I further aim to provide a construction having novel coating inner and outer tubes in combination with a cap, such tubes being capable of reduction in length, if desired, as the contained material is dispensed.

Various additional objects and advantages will be evident from a consideration of the description following taken in connection with accompanying drawing illustrating an operative embodiment.

In said drawing—

Figure 1 is a view of the improved tube in side elevation, being partly broken away to disclose details;

Figure 2 is a longitudinal section taken on the line 2—2 of Figure 1;

Figure 3 is a longitudinal section taken on the line 3—3 of Figure 2;

Figure 4 is a plan view of the tube;

Figure 5 is a horizontal section taken on the line 5—5 of Figure 3, and

Figure 6 is a side elevation, partly broken away, of the cap.

Referring specifically to the drawing wherein like reference characters designate like or similar parts, an outside tube is provided at 10 open at both top and bottom. This tube may be of stiff cardboard, although capable of manufacture from various material. The outer wall of the tube 10 is well adapted for the printing of advertising, branding and directions of the manufacturer thereon. The tube is self-supporting and protects the contents of the container or collapsible tube. On its interior, the tube 10 is preferably lined at 11 with a strong sanitary and uncontaminating stiff paper or thin cardboard, the same being adhesively joined or otherwise secured to the inner wall of tube 10 or other part.

Within the tube 10 and its lining 11, I provide an inside tube 12. The latter tube may be made of any suitable material but preferably of a strong sanitary and uncontaminating stiff paper or thin cardboard with its upper end open and bottom end closed as at 13, the same being internally reinforced if desired by a cardboard or paper bottom disc 14.

It will be noted that the inside tube has diamet-

rically opposite elongated slots at 15 open at the outlet end of the tube and extending practically to the bottom thereof.

At the said outlet end I provide a cap 16. This cap may be made of a suitable metal or of a plastic material or any other suitable material. The cap has depending outer and inner walls or flanges at 17 and 18, respectively, surrounding the exterior of outer tube 10 and extending interiorly into the inside tube 12. The flanges 17 and 18 may be clamped or compressed so as to hold the tubes 10 and 12 in place by friction or in the article as sold the tubes 10 and 12 may be temporarily joined to the cap by an adhesive or in any other suitable manner.

The aforesaid slotting of the inside tube 12 provides arcuate walls 19 and such walls are entered in and are slidable through arcuate slots 20 provided in the cap 16.

Closure and guide lugs 21 are provided on the outside surface of the flange 18 and are located in the slots 15.

The cap may have any suitable outlet means as for instance, a discharge neck 22, exteriorly screw threaded at 23 and detachably engaged by a screw threaded closure 24.

Both the outside tube 10 and the inside tube 12 may have weakened or scored lines thereon at 25 and 26, respectively, enabling portions of such tubes to be detached or torn from the remainder as the contents of the inside tube 12 are dispensed or progressively diminishes.

The operation is suggested particularly in Figure 2 where it will be observed that the inside tube 12 has been moved to an elevated position in dotted lines. Such inside tube is slidable relatively to the outside tube as the contents is dispensed, that portion of the inside tube 12 at the walls 19, which project above the cap, being severed along the lines 26. In addition, the outside tube may be severed to correspond along the line or lines 25, at the base of the latter.

Various changes may be resorted to provided they fall within the spirit and scope of the invention as hereinafter defined by the appended claims.

I claim as my invention:

1. A collapsible tube structure comprising an outside tube, an inside tube within the same, a cap carried by the outside tube provided with slot means, and means interfitting said inside tube and cap for relative sliding movement of the tube through said slot means in the cap in dispensing the contents of the inside tube.

55 2. A collapsible tube structure comprising an

outside tube, an inside tube therein and slidable relatively thereto, a cap carried by the outside tube provided with slots, said inside tube having slots providing portions slidable in the first-mentioned slots, and means on the cap interfitted in one of the slots of the inside tube.

3. A collapsible tube structure comprising an outside tube, an inside tube therein and slidable relatively thereto, a cap carried by the outside tube, said inside tube and cap having slots enabling relative sliding movement of the inside tube and cap, said cap having lugs extending into slots of the inside tube.

4. A collapsible tube structure comprising an outside tube, an inside tube therein and slidable relatively thereto, a cap carried by the outside tube, said inside tube and cap having slots en-

abling relative sliding movement of the inside tube and cap, and depending flanges on the cap respectively engaging the outer surface of the outside tube and the inner surface of the inside tube.

5. A collapsible tube structure comprising an outside tube, an inside tube therein and slidable relatively thereto, a cap carried by the outside tube, said inside tube and cap having slots enabling relative sliding movement of the inside tube and cap, and depending flanges on the cap respectively engaging the outer surface of the outside tube and the inner surface of the inside tube, and lugs on the outer surface of the inner 10 flange entering the slots of the inside tube.

BURL E. HARMAN.
